DRILL SHARPENING APPARATUS

Frank Henry Zachow, Tacoma, Wash.

Application October 11, 1956, Serial No. 615,325

3 Claims. (Cl. 51—125)

This invention relates to drill sharpening apparatus of the class designed for use in sharpening twist drills with emery wheels or other abrasive members.

It is the general object of this invention to provide drill sharpening apparatus for sharpening drills of various sizes efficiently and accurately.

It is another object of the present invention to provide drill sharpening apparatus which sharpens the drill symmetrically.

Still another object of the present invention is the provision of drill sharpening apparatus which by a simple adjustment can be used for grinding the angular cutting edge in the desired position on the drill.

Still a further object of the present invention is the provision of drill sharpening apparatus which advances the drill toward the sharpening stone to a predetermined point where its forward motion is arrested positively.

Still another object of this invention is the provision of drill sharpening apparatus which makes possible clear observation of the drill at all times while it is being sharpened.

Another object of this invention is the provision of drill sharpening apparatus which is of simple inexpensive construction, which is safe and easy to use, and which is adapted for use in home workshops as well as in industrial establishments.

The manner in which the foregoing and further objects of this invention are accomplished will be apparent from the accompanying specification and claims considered together with the drawings wherein:

Fig. 1 is a plan view of the herein described drill sharpening apparatus;

Fig. 2 is a view in front elevation looking along line 2—2 of Fig. 1;

Fig. 3 is a view in side elevation of the presently described drill sharpening apparatus; and

Fig. 4 is a sectional view taken along line 4—4 of Fig. 3 and illustrating the manner of mounting the apparatus.

Generally stated the drill sharpening apparatus of my invention includes a base and guide means directed toward an abrasive member against which the drill is to be sharpened, the guide means mounting the base for reciprocative movement toward and away from the abrasive member. Stop means are provided for controlling and limiting the forward movement of the base.

A bed is mounted on the base at a predetermined angle with respect to the abrasive member. Drill holding means are seated in the bed alternately in upright and inverted positions for contacting in turn the respective cutting faces of the drill with the abrasive member.

Considering the foregoing in greater detail and with particular reference to the drawings:

The herein described apparatus is mounted on a base member 10 which may conveniently comprise a block of wood of suitable dimensions cut away to form a recess 11. The base member in turn is mounted on guide means for longitudinal reciprocation with respect to an abrasive member such as the emery wheel 12.

2

In the illustrated embodiment, the guide means comprises a track member 14 formed with a longitudinal groove or track 16 and a longitudinal passageway 18 which affords clearance for the other elements of the assembly, as will be apparent hereinafter. The track is aligned with the axis of wheel 12 and is affixed to a work bench or other rigid structural member by suitable means such as screws 20.

The under surface of base 10 is formed with guide strip 22. The meeting surfaces of base 10 and member 14 may be polished for sliding engagement so that the base may be moved easily back and forth toward and away from emery wheel 12, being guided by strip 22 in track 16.

In order to sharpen the drill symmetrically, means are present for controlling the advancement of base member 10 and for stopping it at a predetermined point. Such means in the illustrated form comprises a cam 24 keyed to a rotatable shaft 26 and actuatable by a knurled wheel 28 which also is keyed to the shaft.

Cam 24 has a spiral shaped peripheral surface 30 and is positioned with respect to a stop member 34, which is rigid to stationary track 14, in such a manner that as the cam is turned in a counterclockwise direction the cam surface engages the side surface of stop 34, which accordingly acts as a cam follower. This makes possible the controlled advancement of base member 10 in the direction of emery wheel 12. When the operator pushes base 10 forwardly in his right hand while simultaneously turning knob 28 in a counterclockwise direction to his left, the base may be advanced until the drill surface just touches the side surface of the emery wheel and is ground sufficiently to sharpen it. Thereupon its advancement is stopped.

For mounting the drill on the base 10 there is provided a bed which lies obliquely at a predetermined angle with respect to the working surface of emery wheel 12. This bed may comprise a pair of oppositely disposed angle irons 36, 38 suitably fastened to the base member 10, as by means of screws 40. The side edge of at least one of the angle irons, for example angle iron 38, is bent inwardly substantially at right angles to form a retaining tab 42.

The means employed for holding the drill 44 to be sharpened include a pair of plates 46, 48. These plates are adapted to seat in the bed fastened to base 10 and are formed with opposed ribs 50, 52 dimensioned to receive the drill.

Clamping means are present to clamp the drill between the plates, thereby holding it securely in place during the sharpening operation. In the embodiment illustrated particularly in Fig. 2, the clamping means comprises a yoke-shaped member including side segments 54, 56 and connecting segment 58. The side segments are dimensioned to be received in cutaway portions of top plate 46. Also, their lower portions are formed with inwardly turned extensions 60, 62 which project below the plane of the bottom surface of lower plate 48. Accordingly, when the plates are seated in the retaining bed, they are locked against movement in one horizontal direction by the forwardly projecting tab 42, which engages the front surface of side segment 56, and in the opposite direction by the inwardly turned extensions 60, 62, which engage the ends of angle irons 36, 38, respectively.

The clamping assembly is completed by a screw 64 the bottom end of which is secured to top plate 46 and the stem of which is threaded through a grooved nut 66 which penetrates a perforation through connecting segment 58. Hence turning nut 66 raises or lowers top plate 46.

The operation of the herein described drill sharpening apparatus is as follows.

A drill 44 to be sharpened is placed between plates 46, 48 where it nests in the recess formed in part by opposed ribs 50, 52. The drill is adjusted by rotation until its cutting surface is at the desired angle with respect to the side face of emery wheel 12. Nut 66 is tightened, thereby clamping the drill between plates 46, 48. The drill and its holding assembly next are seated in the bed formed by angle irons 36, 38, being restrained against horizontal movement by tab 42 and extensions 60, 62.

The right hand of the operator is placed on base member 10 and his left hand on knurled nut 28. The base member and the drill mounted thereon then are pushed forwardly in the direction of the emery wheel until cam surface 30 of cam 24 is in contact with the side edge of stop member 34.

The operator exerts continuous pressure on base member 10 and at the same time turns knurled nut 28 in a counterclockwise direction, thereby also turning cam 24 and permitting forward movement of the assembly at a rate determined by the contour of the cam and the rate at which it is turned.

The assembly is advanced in this manner until the drill touches the emery wheel and has been sharpened to the desired extent. Thereupon its forward motion is arrested at a point determined by the setting of the cam.

Base 10 then is retracted, the drill and drill holder rotated through 180°, and the holder again nested in the bed formed by angle irons 36, 38. This presents the opposite working surface of the drill to the emery wheel. The assembly is then advanced toward the emery wheel without changing the cam setting until the cam engages stop 34. The opposite working surface of the drill thereupon will be ground symmetrically with the surface ground first.

Accordingly it will be apparent that by the present invention I have provided drill sharpening apparatus by means of which drills can be sharpened symmetrically, easily, and rapidly. In addition, drills of any of the conventional sizes can be sharpened in the same apparatus, and the cutting edge can be ground into the drill at desired positions. Also, the operator can observe the progress of the sharpening operation without hazard.

It is to be understood that the form of my invention herewith shown and described is to be taken as a preferred example of the same and that various changes in the shape, size, and arrangement of parts can be made without departing from the spirit of my invention or the scope of the subjoined claims.

Having thus described my invention, I claim:

1. Drill sharpening apparatus comprising an abrasive member, a base, guide means directed toward the abrasive member and mounting the base for straight line feed

movement toward said abrasive member, bed means mounted on the base at a predetermined angle with respect to the abrasive member, drill holding means removably mounted on the bed and having alternate upright and inverted positions for contacting in turn the respective cutting faces of the drill with the abrasive member, a stop member on one of said base and guide means, and a rotatable member on the other of said base and guide means having a spiral cam surface adapted to engage the stop member, said rotatable member comprising a feed control for said base in the upright position of said drill holding means and a stop for said base in the inverted position of said drill holding means.

2. The apparatus of claim 1 wherein the drill holding means comprises an upright yoke member and screw means mounted in said yoke member for clamping said drill on said drill holding means, said base having a recessed portion disposed vertically below said yoke member for receiving the latter in the inverted position of said drill holding means.

3. Drill sharpening apparatus comprising an abrasive member, a base, guide means directed toward the abrasive member and mounting the base for straight line feed movement toward said abrasive member, bed means mounted on the base at a predetermined angle with respect to the abrasive member, drill holding means removably mounted on the bed and having alternate upright and inverted positions for contacting in turn the respective cutting faces of the drill with the abrasive member, an angular tab on the bed means engageable with the drill holding means for restricting relative movement between the drill holding means and the bed in one horizontal direction, extension means on the drill holding means engageable with the bed for restricting relative movement between the drill holding means and the bed in the opposite direction, a stop member on one of said base and guide means, a rotatable member on the other of said base and guide means having a spiral cam surface adapted to engage the stop member, said rotatable member comprising a feed control for said base in the upright position of said drill holding means and a stop for said base in the inverted position of said drill holding means, and means connected to the rotatable member for rotating the same.
